United States Patent Office

Des. 204,886
Patented May 24, 1966

204,886

HEADSET

Donald L. Kliewer, Bloomington, Minn., assignor to The Telex Corporation, Tulsa, Okla., a corporation of Delaware

Filed June 11, 1965, Ser. No. 85,697

Term of patent 14 years

(Cl. D26—14)

FIG. 4

FIG. 5

FIG. 6

FIG. 1 is a perspective view of a headset, showing my new design.

FIG. 2 is an end elevational view of the headset of FIG. 1.

FIG. 3 is a side elevation view of the inside of one of the headphones used in the headset shown in FIGS. 1 and 2.

FIG. 4 is a top view of a headset.

FIG. 5 is a front view of the headset.

FIG. 6 is a bottom view of the headset.

I claim:

The ornamental design for a headset, as shown and described.
